UNITED STATES PATENT OFFICE.

RUBY EVA PADMAN, OF LAUNCESTON, TASMANIA, AUSTRALIA.

TYPEWRITER.

Application filed March 8, 1924, Serial No. 697,807. Renewed September 24, 1925.

To all whom it may concern:

Be it known that I, RUBY EVA PADMAN, a subject of the King of Great Britain, residing at No. 8 Trevallyn Road, Launceston, 5 in the State of Tasmania and Commonwealth of Australia, have invented a new and useful Improvement in Typewriters, of which the following is a specification.

My invention consists essentially in the 10 combination with a typewriter of a date stamp so arranged as that, on depressing a key, the prearranged date on the stamp is first inked and then printed on the letter, invoice, circular or the like which has 15 previously been placed in position in the typewriter, the date stamp being returned to its normal position on the finger of the operator being lifted from the key.

It is obvious that the date stamp may be 20 applied to a typewriter in various ways, to effect the desired result. I will now describe one means by which a date stamp may be combined with a typewriter, so that, on depressing a key, said date stamp is caused 25 to travel forward, without revolving, against a hinged inking pad in front thereof, thus transferring the necessary amount of ink from the pad to the prearranged date on the date stamp. The further forward movement of the date stamp causes the hinged 30 inking pad to drop, permitting the date stamp to complete its travel and imprint its previously inked date upon the letter, invoice, circular or the like, in position in the 35 typewriter. When this has been effected, and the finger of the operator has been removed from the said key, a spring returns the date stamp to its original position, and another spring returns the hinged inking 40 pad to its original position, ready for impressing the same date on the next letter, invoice, or circular.

The date stamp and its appurtenant parts are contained within a suitable casing which 45 may be formed integral with the right hand end of the frame of a typewriter, or attached thereto in any approved way. In the drawings hereto annexed, I have shown the date stamp and its appurtenant parts attached to the right hand end of the frame 50 of an Underwood typewriter.

Referring to the drawings hereto annexed:—

Figure 1 is a plan view of the date stamp 55 and its appurtenant parts within the casing

before referred to, the cover of the casing being removed.

Figure 2 is a side elevation of Figure 1, one of the sides of the casing being removed.

Figure 3 is a side elevation of the casing, 60 one of its sides being removed, and showing the position of the date stamp and its appurtenant parts, when the key has been depressed to print the necessary date on the letter, invoice, or circular in the typewriter. 65

Figure 4 is a plan view of portion of an Underwood typewriter, showing my invention attached thereto, the date stamp and its appurtenant parts being in the position they occupy after the date has been printed. 70

Figure 5 is a plan view of portion of the casing, showing the means for clamping it to the right hand end of the frame of the typewriter.

Figure 6 is a side elevation of Figure 5. 75

1 is a date stamp consisting of four rubber-faced rollers, carrying in relief the necessary figures and letters to constitute a date. 2 is a horizontal nonrotatable spindle, on which these rollers are mounted. 3 are coiled springs on the said spindle 2, which press the rollers thereon together, and prevent them revolving after the desired date has been set. 4 are horizontal bars attached at one end and at right angles 80 to the respective ends of the spindle 2. 5 are guides on the inside of the casing 6, in which guides the horizontal bars 4 are adapted to slide to and fro. 7 are stops to retain said horizontal bars 4 in said guides 85 90

5. 8 is a horizontal rod immediately behind the date stamp 1, one end of said rod being formed integral with one of the horizontal bars 4 and the other to the opposite one, and consequently adapted to move to and fro 95 with said bars 4. 9 is another horizontal rod extending across the casing at the other end thereof and being formed integral with said casing. 10 is a lazy-tongs lever, one end of which engages with horizontal rod 8 and the other with horizontal rod 9. 11 is a key the inner end of which is a continuation of portion of said lazy-tongs lever, and which key projects through a slot (not shown) in that end of the casing 6 at the opposite end to the date stamp 1. 12 is a 100 container for an inking pad 13, said container being hinged at 14 to the bottom of the front of the casing 6. 15 is a coiled spring for normally keeping said hinged 105

110

inking pad in its closed position. 16 is another coiled spring connected at one end to the back of the casing, and, at its other end, to that portion of the lazy-tongs lever adjacent thereto. 19 is the clamp for clamping the casing 6 to the right hand end of the frame of the typewriter.

As will be clearly understood, on depressing the key 11, the lazy-tongs lever 10 is caused to expand against the resistance of the spring 16, thus causing the date stamp 1 to travel forward, as previously explained, and without revolving against the hinged inking pad 13. The further forward movement of the date stamp overcomes the resistance of the spring 15 and causes the hinged inking pad to drop, thereby permitting the said date stamp to complete its travel and print its previously arranged date on the letter, invoice, or circular, in the typewriter. When this has been effected, spring 16, on the removal of the operator's finger from the key 11, returns the said date stamp to its normal position within the casing 6, and spring 15 returns the said hinged inking pad to its closed position, ready for the next operation.

I claim:

1. In a typewriter the combination there-with of a date stamp, means for causing said stamp to travel forward without re-

volving, first against a hinged inking pad which it causes to fall, and secondly, against a letter, invoice, circular, or the like, in the typewriter, in order to impress the necessary date thereon, and springs for returning both said date stamp and hinged inking pad to their normal positions.

2. In a typewriter, a casing built either into or attached to, the right hand end of the frame of the typewriter, a date stamp carried on a horizontal spindle at one end of said casing, a horizontal bar on either side of the casing, and capable of sliding to and fro in guides on the inside of said casing, said bars being each connected at one end to said horizontal spindle, and at right angles thereto, a horizontal rod behind and parallel with said date stamp and capable of moving with said horizontal bars, a horizontal rod near the other end of the casing and parallel with the previously mentioned horizontal rod, a lazy-tongs lever between and connected to said rods, a key, by depressing which said lever is expanded to operate the said date stamp, a hinged inking pad in front of the said date stamp, a hinged cover to said casing, and springs for returning both said date stamp and hinged inking pad to their normal positions, when required.

RUBY EVA PADMAN.
